KEEPER FOR DOORS

George W. Wells, Amesbury, Mass.

Application November 13, 1936, Serial No. 110,624

6 Claims. (Cl. 292—340)

This invention relates to certain improvements in a type of keeper which is primarily adapted for use in combination with the latch device disclosed in my Patent No. 2,034,363 dated March 5, 1936.

In the form of keeper device disclosed in my said patent, and the forms shown in my pending application 82,462 filed May 29, 1936, and Patent 2,066,438 dated Jan. 5, 1937, the so-called "safety" 10 feature is not as reliable as is desirable.

The necessity of this "safety" feature arises when the operating handle is moved by accident, or otherwise, and is released without opening the door, with the result that the latch member is 15 either slightly lowered or, if lowered to the full extent, is partly raised again upon release of the handle.

Under these conditions the locking pawls or dogs of my previously disclosed keepers swing down and may or may not hold the door against opening movement. For the purpose of catching the door, so that it will not swing free of the jamb, I have provided a deep notch in the latch member which will generally be engaged by the keeper, but this arrangement has not always been 20 effective, and, moreover, the door will have nearly 25 swung free of the jamb before the safety notch is engaged.

It is desirable, therefore, not only to provide 30 an effective keeper device which will prevent the door from opening in any partially lowered position of the latch member, but it is also desirable to provide a device with which the opening movement of the door will be instantly checked in any 35 of the partly lowered positions thereof.

The objects of my invention are to provide a 40 form of keeper which is adapted for use in combination with the latch device of my said patent, and which will effectively check the opening of the door, at any point while partly within the 45 jamb, in any partly lowered position of the latch member, and will perform this function instantly, so that there will be no appreciable opening movement of the door after the operating handle has been released.

I accomplish these objects by providing a form 50 of locking pawl or dog, in some respects similar to those shown in my said prior patent, but which is so arranged that, while it normally operates in practically the same manner as the corresponding parts shown in my said patent, is so arranged that in case the latch is partly lowered, so that the dog is permitted to swing outward, its pivotal point will be transferred outwardly to another point, so that the latch engaging end of

the dog will be swung on a radius of increased 5 inclination and length and will then be swung downward to a lower point than that to which it would be swung on the pivot from which it normally swings, so that the pressure of the end of the dog on the latch is instantly increased to such an extent that further opening of the door is effectively checked.

For a more complete disclosure of my invention reference is now made to the following specification, in connection with the accompanying drawing in which:

Fig. 1 is front elevation of a door and jamb section to which my improved form of keeper has been applied.

Fig. 2 is a side elevation of a keeper embodying my invention.

Fig. 3 is a sectional view at line 3—3 of Fig. 2.

Figs. 4 and 5 are views similar to Fig. 2 showing the parts in different positions, and under 20 different conditions.

Fig. 6 is a detail view of one of the pawls and the parts immediately associated therewith.

In the drawing 10 indicates a portion of a door and 11 a portion of its jamb, a latch device such as is disclosed in my said prior patent being mounted on the door, said device comprising the supporting projection 12, on which the vertically moving latch member 13 is mounted, the position of which is controlled by the handle operated cam shaft 14. The jamb is preferably provided with a horizontally disposed support 15 on which the projection 12 is supported in the closed position of the door, as shown in Figs. 4 and 5.

According to my invention I provide a pair of 35 holding dogs 16 and 17, which are arranged successively to engage the top surface of the latch member 13, as the door is closed, and, while I prefer to employ two of said dogs, instead of a single dog, a single dog is perfectly effective. Both dogs are identical in construction, so that a description of one of them will suffice.

Each dog is formed of rigid sheet metal and shaped in U-form in transverse section to provide a middle and two side portions, the lower end of said middle portion being extended to form a slightly inwardly curved tongue 18, the lower end or bottom edge of which is horizontal and is of a length corresponding to the width of the latch member 13, or the extent to which it projects 50 from the door. Each side portion is provided at its top edge with two convexly shaped projections 20, 22, to form pivotal portions, and the top edge between said projections is of concave formation, forming a recess 23.

It is to be particularly noted that the distance from the end of the tongue 18 to the middle of the portions 20 is less than the distance from the end of the tongue to the middle of the portions 22.

5. A stiff metal strip 24 is riveted to the under-side of the top of the keeper casing 25 and is formed to provide two convexly curved portions 26, which conform in curvature to the recesses 23 of the dogs. Also transverse grooves 27 and 10 27' are formed in the under side of the strip 24 at the ends of the curved portions, which are adapted to receive pivotal projections 20 and 22. A spring 28 is arranged to hold each dog with its recessed ends 23 engaged with the curved portions 26 and its projections 20, 22 respectively engaged in the grooves 27, 27', one end of the spring being attached to a lug 29 struck out from the middle portion of the dog, adjacent its lower end, and the other end of the spring being extended thru a slot 30 in the strip 24 and being connected to a cross pin 31, which rests on the upper side of the curved portion 26. The spring is thus located between the sides of the dog, and is so arranged that it normally acts to hold the 20 dog to which it is attached in the position of Fig. 2, in which position it tends to resist swinging movement of the pawl either inwardly, or outwardly.

While it is desirable to provide a support, as 30 15, on the jamb for the rigid supporting member 12 on the door, it will be understood that whether the support 15 is or is not provided, or whether, if, it is provided, it is rigid or slightly yielding, in any event the latch member 13 is carried in 35 a substantially predetermined horizontal path and is normally held in the position of Fig. 2, so that, when the door is closed, the pawls are swung inwardly from a normal and approximately vertical position, on their inner projections 20 as 40 pivots, as shown in Fig. 4, in which position the tongues 18 at their lower ends are firmly engaged with the top surface of the latch member 13, and firmly hold the door against opening movement in a multiplicity of positions. In practice the top surface of member 13 is provided with closely spaced, shallow corrugations which extend in parallel relation to the edge of the tongue 13, but the holding effect will be practically the same if the top surface is smooth. If 50 the operating handle is moved so that the latch member is lowered to its fullest extent, it will be carried out of contact with the dogs, so that if held in this position, the door may be opened.

As thus far described, the operation is substantially the same as that disclosed in my said patent. If, however, the operating handle should be turned sufficiently to permit a partial lowering of the latch member, or is turned sufficiently to permit complete lowering thereof, and if the handle is then released, the door in either instance being permitted to remain closed, the result will be that the latch member will be held in a partly lowered position, as indicated for example in Fig. 5. Under these conditions, with my previously disclosed forms of keepers, there is danger that the dogs will fail to engage the latch member with sufficient force to prevent opening of the door, although in most instances they will engage in the safety notch and prevent complete opening.

70. With my improved construction, however, the following action takes place under the conditions outlined, assuming the parts to be in the position of Fig. 4.

75. If the handle is operated, without opening the

door, the latch member will be lowered sufficiently to permit the dogs to swing outward to their normal position, and when the handle is released the member will be lifted again until it is forced against the dogs, while in this position, as shown in full lines in Fig. 5.

Under this condition any tendency to swing the door outward will tend to swing the dogs outward, so that the pivotal point of engagement of each dog will instantly be transferred to the outer projections 22 and any further outward swinging movement will be from this point as a center. Under these conditions the radius from the center of motion to the end of the tongue 18 will be transferred from an approximately vertical position to an inwardly inclined position, as indicated by the dotted lines X, in Fig. 5. As the center of motion has thus been moved outward, and the distance from the center to the end of the tongue will have been increased, it will be apparent that the end of the tongue 18 will tend to swing downward, which it would not tend to do if it were being swung from the inner pivotal point 20. As a result the dogs will instantly firmly engage the latch member in a position which is at least as effective as under the normal conditions shown in Fig. 4. While the dogs may under these conditions swing out to the dotted line positions of Fig. 5, in actual practice, the outward swinging movement from the full line position of Fig. 5, will be very slight.

If, however, the latch member should yield to some extent, the dogs would swing down correspondingly and hold the door against opening. The door will thus be effectively held against accidental opening under all conditions. When either of the dogs swings outward from the position of Fig. 2, its spring 28 will be stretched, so that the spring constantly tends to return the dog to the normal position of Fig. 2 whether it is swung inward or outward from this position.

With this construction the range of position of the latch member in which the dogs will engage it and effectively lock the door against opening movement is substantially increased, as compared with my previously disclosed constructions, and it is effective in locking the door against opening movement in any position in which the door is closed sufficiently to permit engagement of the outermost dog with the latch member. The arrangement is also instantly effective in all of the engaged positions, as the lower end of one or both of the dogs will be held firmly against the latch member in all of these positions and any tendency of the door to move outward causes the pressure of the dog on the latch member to be increased instantly, so that any appreciable opening of the door will be prevented.

The construction is also advantageous in that it is of sufficient strength effectively to resist all strains to which it is liable to be subjected, and, from a manufacturing standpoint, is advantageous as it may be easily constructed and assembled.

I claim:

1. A keeper for use on the jamb of a door arranged for engagement with the horizontally disposed top face of a latch member on the door and comprising a casing having a depending dog mounted therein, said dog having a latch member engaging face at its lower end and an inner and an outer pivotal engagement with the casing at its upper end, so arranged that as the dog swings inwardly from its normal position it will pivot at the inner point of engagement and as

65

70

75

it swings outward from said position it will pivot at the outer point of engagement.

2. A keeper for the jamb of a door arranged for engagement with the horizontally disposed top face of a latch member on the door, and comprising a casing having a dog mounted therein in a depending position, said dog having a latch member engaging face at its lower end and a pivotal engagement with the casing at its upper end at 5 an inner and an outer point, and a spring arranged to hold said dog in an intermediate position in which it is engaged with the casing at both pivotal points and permits the dog to swing inwardly from said position on the inner point 10 15 as a pivot and to swing outwardly therefrom on the outer point as a pivot.

3. A keeper for the jamb of a door arranged for engagement with the horizontally disposed top face of a latch member on the door, and comprising a casing having a dog mounted therein in a depending position, said dog having a latch member engaging face at its lower end, and having a loose engagement at its upper end with the casing at an inner and an outer pivotal 20 25 point, and a spring arranged normally to hold said dog in a position in which it engages the casing at both pivotal points and permits the dog to swing inward from said position on the inner pivotal point and to swing outward therefrom on 30 the outer pivotal point.

4. A keeper for the jamb of a door arranged for engagement with the horizontally disposed top face of a latch member on the door, and comprising a casing having a dog mounted therein in a depending position, said dog having a latch member engaging face at its lower end, and a loose engagement at its upper end with the casing at an inner and an outer pivotal point, the distance from the face at the lower end of the 35 40 dog to the inner pivotal point being less than the distance therefrom to the outer pivotal point, and a spring arranged to hold said dog in engagement with the casing at both pivotal points and to yield to permit the dog to swing in either

direction on one or the other of said pivotal points.

5. A keeper for the jamb of a door arranged for engagement with the horizontally disposed top face of a latch member on the door, and comprising a casing having a dog mounted therein in a depending position, said dog having a middle portion and two side portions, said middle portion having a latch engaging face at its lower end and said side portions each having at their 10 upper ends a pivotal point of engagement with the casing adjacent the middle portion and a pivotal point of engagement therewith at a substantial distance outwardly from said middle portion, and a spring disposed between said side portions 15 and connected at its lower end to the dog adjacent its said face, and at its upper end to said casing, in position normally to hold all of said pivotal points in engagement with the casing and to yield to permit swinging movement of the dog 20 either inwardly or outwardly on the corresponding inner or outer pivotal points.

6. A keeper for the jamb of a door arranged for engagement with the horizontally disposed top face of a latch member on the door, and comprising a casing having a dog mounted therein in a depending position, said dog having a middle portion and two outwardly extending side portions, said middle portion having a latch engaging face at its lower end and said side portions 25 30 each having two projecting portions at its top edge, one adjacent the middle portion and the other at the outer edge thereof and said casing having recesses to receive said projecting portions to permit pivotal engagement thereof with the casing, and a spring disposed between said side portions and connected at its lower end to the middle portion and at its upper end to the casing, normally to hold said projecting portions 35 40 in position in said recesses and to yield to permit inward or outward swinging movement of the dog on the inner or outer projecting portions, respectively.

GEORGE W. WELLS.
